UNITED STATES PATENT OFFICE.

GEORGE T. JOHNSON, OF COLUMBUS, OHIO, ASSIGNOR TO THE BUCKEYE STEEL CASTINGS COMPANY, OF COLUMBUS, OHIO.

COUPLER YÖKE.

Application filed December 16, 1924. Serial No. 756,342.

This invention relates to draft-rigging for cars and has special reference to the front hooded end of the draft yoke, the object being to so construct the end of the yoke as to provide as close a fit as possible between the coupler shank and the yoke. As the yoke is stationary under buffing stresses, the coupler shank necessarily slides rearwardly in the yoke and, of course, wear takes place as the parts remain in service so that eventually the coupler becomes very loose in the yoke and moves around unrestrained. Under these conditions, a rough track frequently causes such violent vertical vibrations of the coupler that its parts may move from coupled to uncoupled position. By the present invention, the coupler, in order to move upwardly, must lift the yoke and the draft gear carried by the yoke and the weight of these parts is sufficient to retard or break up the vertical vibration so that there is no danger of the coupler parts being dislodged from the coupled position. The invention is illustrated in the accompanying drawings and will be hereinafter fully set forth.

ness so as to present inner parallel surfaces adapted to closely engage the top and bottom, respectively, of the shank. These opposed parallel surfaces extend from the extreme forward edges of the roof and floor to the opening through the yoke defined by the rear ends of the side walls 1 so that they furnish substantial guides for the coupler shank in its horizontal movement and effectual stops for its vertical movement. A 65 transverse groove 5 is formed in the roof and a like groove is formed in the floor thereby reducing the wear upon the shank and the weight of the yoke without any loss in efficiency. A socket or chamber 6 is formed in the rear end of the roof and also in the rear end of the floor for the purpose of reducing the dead weight of the yoke without any reduction in its strength or in the area of the shank guiding surface. 70 75

It will be readily seen that the described construction presents substantial guides to the top and bottom of the coupler shank which will effectually resist rocking movement of the shank in a vertical plane, it being noted that the greater portions of the

80

In the drawings,

Figure 1 is a view, partly in longitudinal section and partly in side elevation, of one embodiment of the invention;

30 Figure 2 is a view of the same, partly in horizontal section and partly in plan;

Figure 3 is a view, similar to Figure 1, showing another form of the invention;

Figure 4 is a view, similar to Figure 2, of the form shown in Figure 3;

Figure 5 is a transverse section on the line 5-5 of Figure 4; corresponding

Figures 6 and 7 are views, corresponding to Figures 1 and 2 respectively, showing a side view of the invention.

Figure 8 is a section on the line 8—8 of

Figures 9 and 10 are views, similar to Figures 1 and 2 respectively, showing a fourth form of the invention.

The yoke has side walls 1 provided with longitudinal slots 2 to receive the ends of

the usual key operatively connecting the coupler shank with the yoke. Ordinarily, the top and bottom of the hood do not closely engage the shank of the coupler or are so formed that only their end edges engage the shank, but according to my invention, as shown in Figures 1 and 2, the roof 3 and the floor 4 of the hood are increased in thick-

ness so as to present inner parallel surfaces adapted to closely engage the top and bottom, respectively, of the shank. These opposed parallel surfaces extend from the extreme forward edges of the roof and floor to the opening through the yoke defined by the rear ends of the side walls 1 so that they furnish substantial guides for the coupler shank in its horizontal movement and effectual stops for its vertical movement. A transverse groove 5 is formed in the roof and a like groove is formed in the floor thereby reducing the wear upon the shank and the weight of the yoke without any loss in efficiency. A socket or chamber 6 is formed in the rear end of the roof and also in the rear end of the floor for the purpose of reducing the dead weight of the yoke without any reduction in its strength or in the area of the shank guiding surface.

It will be readily seen that the described construction presents substantial guides to the top and bottom of the coupler shank which will effectually resist rocking movement of the shank in a vertical plane, it being noted that the greater portions of the slots 2 are located between vertical planes touching the front and rear ends of the roof and floor. 80

In Figures 3, 4 and 5, the shank-engaging surfaces of the roof and floor are defined by ribs 7 extending longitudinally of the floor and roof, respectively, from the front to the rear edges thereof, the spaces between the ribs serving the same purpose 90 as the grooves 5 in Figure 1.

In Figures 6, 7 and 8, the floor 8 and the roof 9 are free of grooves or other interruptions but in the top and bottom exterior surfaces of the yoke are longitudinal recesses 25 10 to eliminate excess weight.

In Figures 9 and 10, the guiding and limiting surfaces of the roof 11 and floor 12 are not continuous and consist essentially of a transverse flat shelf or projection 13 at the front end of the hood and a flat-faced transverse rib or lug 14 at the rear end thereof, weight-reducing sockets 15 being provided in the front edge of the rib or lug as shown. 100

In all the described forms, positive guides 105 for the coupler shank are provided, particularly at the inner ends of the side walls of the hood, and these guides effectually resist vertical vibration of the coupler.

Having fully described my invention what 110

I claim as new and desire to secure by Letters-Patent, is:—

1. A draft yoke for cars having a hooded end with a floor and a roof, the opposed surfaces of the floor and the roof being parallel with the longitudinal axis of the yoke and arranged to closely engage the top and bottom of a coupling shank, said surfaces having transverse channels between their ends and the rear portions of the roof and the floor being vertically expanded.

2. A draft yoke having a hooded end with a floor and a roof, the opposed surfaces of the floor and the roof being parallel with the longitudinal axis of the yoke and arranged to closely engage the top and bottom of a coupling shank, said surfaces having transverse channels between their ends and

the rear portions of the roof and the floor being vertically expanded.

3. A draft yoke having a hooded end with a floor and a roof, the exterior surfaces of the floor and roof converging forwardly, and the inner opposed surfaces of the floor and the roof having flat portions parallel with the longitudinal axis of the yoke arranged to closely engage the top and bottom of a coupling shank whereby to prevent relative vertical angling of the shank and yoke, the foremost extremities of said flat portions being merged in the front edges of the roof and floor respectively, and the rearmost extremities of said surfaces being located at the front ends of the side openings of the yoke.

In testimony whereof, I have signed this specification.

GEORGE T. JOHNSON.
